& Naughton*[57] CLAIM

The ornamental design for a quick coupler mount for front of farm tractor, as shown and described.

DESCRIPTION

FIG. 1 is a front elevational view of a quick coupler mount for front of farm tractor showing my new design;
 FIG. 2 is a left side elevational view thereof, the right side being a mirror image of that shown;
 FIG. 3 is a rear elevational view thereof;
 FIG. 4 is a top plan view thereof; and
 FIG. 5 is a bottom plan view thereof.
 The broken lines in FIG. 2 of the drawing are for illustrative purposes only.
